(57) **CLAIM**

The ornamental design for an earphones with charging case, as shown and described.

DESCRIPTION

FIG. 1 is a perspective view of the earphones of an earphones with charging case, showing the new design, shown separately to show aspects of the design that are not visible when combined;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the earphones of the earphones with charging case, shown separately to show aspects of the design that are not visible when combined; FIG. 10 is a perspective view of a charging case of the earphones with charging case, shown separately to show aspects of the design that are not visible when combined and in an open configuration;

FIG. 11 is another perspective view thereof;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a perspective view of the earphones with charging case, shown in use with the earphones received in the charging case; and,

FIG. 20 is a perspective view of the charging case of the earphones with the charging case, shown separately to show aspects of the design that are not visible when combined and in a closed configuration.

(Continued)

The broken lines in the drawings depict portions of the earphones with charging case that form no part of the claimed design.
